UNITED STATES PATENT OFFICE

CHARLES M. PETERSEN, OF SHIRLEY, MASSACHUSETTS, ASSIGNOR TO SAMSON CORDAGE WORKS, OF BOSTON, MASSACHUSETTS, A CORPORATION OF MASSACHUSETTS

CORD-MAKING MACHINE

Application filed March 16, 1929. Serial No. 347,607.

The invention relates to an improved cord-making machine and especially to a machine for making braided cord.

A great variety of machines have been devised for making braided cord which for the most part have possessed some particular advantage as advance was made in the art, but I know of no machine relatively narrow and compact capable of receiving and operating any large number of heavily laden spools. It is accordingly the object of my invention to provide a machine having such capability.

Though great progress has been made in the art of cord making machines since the days of the early machines, yet these early machines possessed many advantages in their essential principles, both in point of simplicity of construction, facility of operation and easy maintenance and repair. An example of such machine is shown in the patent to J. P. Tolman, No. 340,835 of April 27, 1886, in which the spools were borne by travelers moved circuitously by carrier gears from one position of rest in a holding ring to another position along a looped track or way. Perhaps the most essential objection to this old machine of the Tolman type, or for that matter to earlier machines of the same general type, but in which the travelers were governed in their movements by some form of movable switch or selector as distinguished from a looped track, was that only spools of relatively small diameter carrying comparatively little strand could be used without unduly widening the machines, especially when the number of the spools was increased, for the reason that the spools would interfere and could not pass one another in the operation of the machine. It is accordingly a further object of my invention to provide a machine of the early type as above referred to, in point of principle, but one capable of carrying a large number of spools all of relatively large diameter or strand-carrying capacity, and this without increase in the width of the machine.

The invention can best be seen and understood by reference to the drawings in

Fig. 1 is a side elevation of the machine. Fig. 2 is a section on line 2—2 of Fig. 1. Fig. 3 is a section on lines 3—3 of Fig. 2 and Fig. 4.

Fig. 4 is a section on line 4—4 of Fig. 3. 55 Fig. 5 is a section on line 5—5 of Fig. 1. Fig. 6 is a section on line 6—6 of Fig. 1. Fig. 7 is a section on line 7—7 of Fig. 6. 60 1 represents the bed of the machine having a centerpiece 2. Rising from the centerpiece 2 with bearing thereon by means of a flanged foot 3 is a stationary center post 4 preferably made hollow in order that a core 5 may be introduced to pass upwardly 65 through it when the braided cord is being made with a core.

Rising also from the base with bottom ends located within butts 6 thereon are posts 7. These posts are circumferentially arranged, and fixed thereto to lie between them 70 in superposed planes widely separate from one another are internally toothed holding rings 8 and 9, respectively. These rings apart from their normal functions in the operation of the machine, act as braces, reinforcing the uprights and giving rigidity to the entire machine. In addition to their internal teeth both the holding rings 8 and 9 are provided with spaced notches 75 interposed at regular intervals between their respective teeth, the holding ring 8 being provided with notches 10 and the holding ring 9 with notches 11. These notches are adapted to receive and hold at intervals in the operation of the machine the spool carrying spindles borne by the travelers as will later be explained. 80 85

Loosely embracing the fixed center post 4 and rotatable around this post is a vertical sleeve 12. This sleeve has bearing to 90 turn at its bottom end on the centerpiece 2 of the frame and flanged foot 3 of the center post 4. At its top the sleeve is contracted to fit snugly around the center post which provides an internal bearing for it. 95

Fixed to the sleeve 12 with outward extension therefrom to lie beneath the holding ring 8 is a cam table 13 having a looped track or way 14 therein, within which run travelers 15 bearing spindles 16 which carry 100

frames 17 containing the strand carrying spools 18.

Resting to turn upon the cam table 13 are a number of carrier gears 20. Each of these gears is fixed to a rotatable vertical shaft 21 extending through the cam table and held from vertical displacement by a nut 22 on the lower end of the shaft with bearing against the under side of the cam table. The carrier gears 20 are arranged in the same plane with the holding ring 8 and the teeth thereof are in mesh with the internal teeth of this ring so that the carrier gears will be rotated as the cam table is turned. Each of the carrier gears is provided around its peripheral edge between its teeth at regular intervals with notches 23 which receive and hold at intervals in the operation of the machine, the spool carrying spindles 16 borne by the travelers 15.

The cam table 8 is turned by means of a pinion gear 25 which engages the toothed peripheral edge of this table. The pinion gear 26 is fixed to a vertical shaft 27 which turns within hubs 28 borne by brackets 29 fixed to the holding rings 8 and 9 respectively, and this preferably through connection with adjacent ones of the posts 7 which support these rings. The shaft 27 bears on its lower end a bevel gear 30 co-operating with which is a bevel gear 31 carried by a driving shaft 32 turned by any suitable source of power, not shown.

The braiding operation effected by the movement of the spools with relation to a central braiding point or die consequent upon circuitous movement of the travelers 15 through co-operating action of the cam table, carrier gears and holding ring upon the turning of the cam table, is like that referred to in Letters Patent No. 340,635 previously referred to and will be fully understood in the light of this patent. During this operation the strands 33 off the various spools will be directed upwardly through the spindles 16 (made hollow) on which the spools are arranged, and then redirected by arms 36 on the top ends of the respective spindles to the braiding point or die 37. This die is borne by a die support 28 attached to any suitable fixed part of the machine.

It will be observed that a relatively large number of strand carrying spools are employed, some twenty spools, according to the example of machine shown in the drawings, and these spools are operated off the one cam table in a machine of normal size, yet the machine would possess no practical utility for the reason that the spools would necessarily

have to be very thin spools diametrically to permit of their passing one another in the operation of the machine. Consequently as they could carry but little strand material this would have to be frequently replenished. Accordingly reference will now be made to that phase of the invention which permits of a large number of spools of relatively large diameter and strand carrying capacity being operated off travelers working on the one cam table without increasing the width of the machine.

The result is initially obtained by making the spool carrying spindles relatively long spindles, and then arranging the spools carried by them in sets lying in separate superposed planes. Three sets of spools are shown in the present example of the machine, 40 representing the spools of the bottom set, 41 the spools of the next set above, 45 and 42 the spools of the upper or top set. The further arrangement of the spools is such that those spools will lie in different sets or planes which are borne by spindles attached to travelers that pass near one another as they traverse during the operation of the machine over the one cam table, thus keeping the spools, which might otherwise engage one another, widely separated at all times, so that spools of relatively large diameter and strand carrying capacity can be used.

Inasmuch as relatively long spindles are borne by the travelers 15, which spindles carry more or less weighty spools, it becomes necessary that provision be made for supporting and guiding the top ends of the spindles in order that the spindles will be maintained to run true and rigid and not cramp the travelers by which they are carried. An arrangement accordingly is provided at the head of the spindles which in many respects is like that at the bottom. It comprises the internal toothed holding ring 9 provided with periodically spaced notches 11 between its teeth as previously described. This holding ring is maintained by the posts 7 in precise vertical alignment with the holding ring 8 at the bottom of the spindles and all the parts of the top ring are in precise vertical alignment with those of the bottom ring including its teeth and respective notches. Co-operating with the internal toothed edge of the holding ring 9 are carrier gears 43. These carrier gears are precisely like the carrier gears 20 at the bottom of the spindles and are provided with periodically spaced notches 44 between their respective teeth for receiving the top ends of the spindles precisely as notches 23 are provided between the teeth of the bottom carrier gears for receiving the bottom ends of the spindles. The teeth of the top carrier gears and notches are all precisely in vertical alignment with those of the bottom carrier gears.

tom carrier gears. The top carrier gears are fixed to the same rotatable vertical shafts 21 that carry the bottom carrier gears and accordingly turn simultaneously therewith.

5 Mounted upon the fixed holding ring 9 is an externally toothed cam table 45 which corresponds relatively with the cam table 13 at the bottom of the spindles. The cam table 45 is retained to turn upon the holding ring 9 by means of an annular flange 46 on the under side thereof, which runs within a groove 47 formed in the top side of the holding ring 9. The cam table 45 is provided on its inside with a cam edge 48 which is precisely like the outer cam edge presented by the looped track or way 14 on the cam table 13, and this cam edge 48 on the upper cam table lies in precise vertical alignment at all points with the outer cam edge presented by the looped track on the bottom cam table. Both cam tables are combined to rotate together by vertical shafts 50 connecting the two tables. The 20 peripheral gear teeth on the two cam tables are in vertically coincident alignment. The upper cam table is rotated simultaneously with the lower cam table by means of a pinion gear 51 engaging its toothed edge, and 25 this pinion gear is fixed to the same shaft 27 as turns the pinion gear 25 which drives the lower cam table, both pinion gears 51 and 25 being precisely alike.

Carried by the tops of the spool carrying 30 spindles 16 borne by the travelers 15 is another set of travelers 54. These travelers are held in engagement with the cam edge 48 of the cam table 45 by means of carrier plates 55 on the heads of the carrier gears 43, and fixed to these gears by pins 56. The carrier plates are like the carrier gears to which they are fixed, being provided with notches 57 vertically coincident with the notches 44 in the carrier gears 43, but have 40 no teeth. The carrier plates operate through the spindles contained in their respective notches to hold the travelers 54 in proper engagement with the cam edge 48 of the cam table 45. In fact the carrier plates 55 perform the same relative function in the 45 retention of the travelers 54 with relation to the cam edge 48 presented by the upper cam table as does the inner cam edge to the looped track or way 14 on the lower cam table 13 but the arrangement permits of the 50 spool carrying spindles being extended above the upper cam table to permit of the strands, issuing from the top ends of the spindles, passing to the braiding point.

55 Thus the spool carrying spindles are retained at opposite ends of the machine to run vertically true and rigid without cramping, and relieving the travelers 15 carrying these spindles of strain which would otherwise come upon them. Other means than

that shown, however, may be employed without departing from the essential principles of my invention.

Having thus fully described my invention, I claim and desire to secure by Letters Patent of the United States:—

1. In a cordage machine having a number of spindles and means common to all said spindles for moving them to describe circuitous paths with passage by one another, 75 spools borne by the spindles and arranged in sets lying in separate superposed planes, those spools borne by spindles passing relatively near one another in the operation of the machine lying in separate ones of said 80 planes.

2. In a cordage machine having a number of spindles and means common to all said spindles for moving them to describe circuitous paths with passage by one another, 85 spools borne by the spindles and arranged in sets lying in separate superposed planes, the spools in each set of spools being borne by a certain set of spindles whereby the spindles carrying spools arranged in separate sets may pass relatively near one another in the operation of the machine.

3. In a cordage machine having a number of spindles, mechanism common to all said spindles for moving them to describe 95 circuitous paths with passage by one another, said mechanism including travelers to which the spindles are affixed, and means for controlling the travelers, spools borne by the spindles and arranged in sets lying in 100 separate superposed planes, the spools in each set of spools being borne by a certain set of spindles whereby the spindles carrying spools arranged in separate sets may 105 pass relatively near one another in the operation of the machine.

4. In a cordage machine having a number of spindles, mechanism common to all said spindles for moving them to describe circuitous paths with passage by one another, 110 said mechanism including travelers to which the spindles are affixed at one end thereof, and means for supporting and guiding during their operation the opposite ends of the spindles, spools borne by the spindles and arranged in sets lying in separate superposed planes, the spools in each set of spools being borne by a certain set of spindles whereby the spindles carrying spools arranged in separate sets may 115 pass relatively near one another in the operation of the machine.

5. In a cordage machine of the type specified having travelers movable along circuitous paths with intermittent passage by and 125 relatively near one another, spindles borne by the travelers, and spools borne by the spindles and arranged in sets lying in separate superposed planes, those spools borne by spindles passing relatively near one another in the operation of the machine.

other in the operation of the machine lying in different ones of said planes.

6. In a cordage machine of the type specified having travelers movable along circuitous paths common to all and which travelers have intermittent passage by and relatively near one another in the operation of the machine, spindles borne by the travelers, means for supporting and guiding during their operation the opposite ends of the spindles, spools borne by the spindles and arranged in sets lying in separate superposed planes, those spools borne by spindles passing relatively near one another in the operation of the machine lying in different ones of said planes.

CHARLES M. PETERSEN.
